UNITED STATES PATENT OFFICE.

JOHN L. EAST, JR., OF CLAUDELL, KANSAS.

IGNITION-TESTER.

1,279,305.

Specification of Letters Patent. Patented Sept. 17, 1918.

Application filed June 19, 1917. Serial No. 175,836.

To all whom it may concern:

Be it known that I, JOHN L. EAST, Jr., a citizen of the United States, residing at Claudell, in the county of Smith and State 5 of Kansas, have invented certain useful Improvements in Ignition-Testers, of which the following is a specification, reference being had therein to the accompanying drawing.

The present invention has reference generally to improvements in that class of inventions known as internal combustion engines and more particularly relates to an 10 ignition tester.

As the primary aim and object, the present 15 invention contemplates the provision of novel means for operably receiving and supporting a plurality of spark plugs which are in circuit with the supporting means and with the timer of a motor vehicle whereby 20 a mechanic while turning the engine shaft so as to actuate the timer will be able to observe the actuation of the spark plugs, thus easily determining the cause of misfiring of the engine cylinders generally due to ineffective 25 spark plugs.

It is an additional and equally important 30 object of the present invention to so construct the supporting means that the spark plugs may be readily tested even before being placed in an engine.

The invention as a further improvement 35 consists in the provision of novel means for pivotally connecting the spark plug supporting brackets on the base whereby to permit of the folding of the brackets against the base, thus placing the device in a compact form in order that it may be conveniently carried in a tool box of a motor vehicle.

It is a more specific object of the present 40 invention to provide improved attaching arms on the base for engagement with the engine; to also provide improved means for assuring of the maintenance of the supporting 45 brackets in an upright position.

Among the other aims and objects of the present invention may be recited the provision of a device of the character mentioned with a view to compactness, and in which the 50 number of parts are few, the construction simple, the cost of production low and the efficiency high.

Other improvements and novel details in the construction and arrangement of the 55 various parts of the apparatus will be brought out more in detail in the description

to follow, which for a clear understanding of the invention, should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the spirit of the invention or the principle of operation of the various parts.

The preferred embodiment of the present invention is clearly illustrated in the accompanying drawings, in which:

Figure 1 is a perspective of the device embodying the present invention.

Fig. 2 is an enlarged transverse section taken through the base, the supporting brackets being shown in elevation, and

Figure 3 is a fragmentary top plan of Fig. 2.

Similar characters of reference are employed in all of the above described views to indicate corresponding parts.

Referring now, more particularly, to the accompanying drawings, there is provided an elongated relatively flat rectangular supporting base 1 formed of conducting material and provided adjacent one marginal edge with spaced longitudinally extending slots in each of which is pivotally and slidably connected an integral pair of spaced non-conducting attaching arms 2 through 90 the instrumentality of suitable fastening devices and these arms are adapted for engagement with an engine, as is apparent. It will be readily appreciated that the construction of these arms will vary when employed on different types of motors. Formed integral with the upper surface of the base are a plurality of uniformly spaced ears 3.

With a view toward providing improved means for movably supporting the spark 100 plugs, there is employed a plurality of inverted L-shaped supporting brackets indicated in their entirety by the numeral 4 and formed of conducting material. Each of these brackets consists of a long portion 105 5 the inner end of which is bifurcated to provide spaced ears 6 which are pivotally arranged about one of the ears 3 by means of a suitable pivot pin 7, the connection being such that the arms may be swung longitudinally in one direction so as to engage the base 1 and when in such folded position

may be readily carried in a tool box of a motor vehicle. In order to maintain the brackets in an upright position lugs 8 extend from one side adjacent the ears 6 and contact with the base 1 so as to limit swinging movement and maintain the brackets in an upright position. The outer portions 9 of the brackets 4 terminate in opposed arcuate and resilient clamping arms 10 the outer ends of which are bent outwardly to provide guides 11. As will be appreciated upon reference to Fig. 2 the clamping arms 10 are positioned beyond the vertical plane of the adjacent marginal edge of the base. 15 Spark plugs 12 are insertible between the guides so as to be engaging and supported by the arcuate arms 10.

Each of the spark plugs is electrically connected to a timer 13. In accomplishing this purpose a conducting wire 14 extends from the top of each spark plug and is connected to one of the plurality of uniformly spaced contact arms 15 on the outer edge of the base of the timer 13. The timer of course is of any suitable construction employed on motor vehicles and of course is adapted to be operated during the actuation of the engine of the motor vehicle. A conducting wire 16 has one end connected to the base 1 and the opposite end operably connected to a contact arm 17 rotatably mounted on the timer and arranged to successively engage each of the contact points during rotation. A battery or other source of energy 18 is interposed in the conducting wire 16 and because of the connection between the portions of the supporting brackets 5 with the ears as well as the connection between the clamping arms 10 and the spark plugs 12, 30 it will be appreciated that when the drive shaft of an engine (not shown) is turned the timer will be rotated so as to successively engage each of the contact points 15 and close the circuit whereupon if the spark plugs are in good condition the spark will 35 jump the gap during the time the arm 16 contacts with each of the contact points 15.

If the spark fails to jump the gap in any of the spark plugs the mechanic or other person testing the spark plugs will know at 50 a glance that one of the cylinders of the motor is misfiring. It will also be appreciated that by the making of a few slight modifications the present device can be used for testing spark plugs in a shop or at a 55 factory.

As many changes could be made in the above construction and many apparently widely different embodiments of this invention could be made without departing from 60 the scope thereof, and it is intended that all matter contained in the above description or shown in the accompanying drawings shall be interpreted as illustrative and not in a limited sense. It is also to be understood 65 that the language used in the following claim is intended to cover all the generic and specific features of the invention herein described and all statements of the scope of the invention, which, as a matter of language 70 might be said to fall therebetween.

Having thus fully described this invention, what is claimed as may and desired to be secured by Letters Patent is:—

A device of the character described including an elongated relatively flat rectangular supporting base formed of conducting metal, means for attaching the base to a suitable support, a plurality of ears formed integral with the upper surface of the base 80 at uniformly spaced intervals, a plurality of L-shaped brackets the outer ends of the long portions of which are pivotally connected to the ears, lugs formed on the inner ends of the long portions and co-operating with 85 the base for maintaining the brackets in an upright position, the brackets being foldable at times to lie upon the base when not in use, and opposed clamping arms formed on the outer ends of the other portion of 90 each of the brackets for receiving and supporting a spark plug.

In testimony whereof I affix my signature.
JOHN L. EAST, JR.
